UNITED STATES PATENT OFFICE.

JOHN HOPSON, JR., OF NEW LONDON, ASSIGNOR TO THE WATERBURY CLOCK COMPANY, OF WATERBURY, CONNECTICUT.

DESIGN FOR A CLOCK-CASE.

SPECIFICATION forming part of Design No. 23,724, dated October 23, 1894.

Application filed September 25, 1894. Serial No. 524,114. Term of patent 7 years.

To all whom it may concern:

Be it known that I, JOHN HOPSON, Jr., of New London, in the county of New London and State of Connecticut, have invented a new 5 Design for Clock-Cases, (Case E;) and I do hereby declare the following, when taken in connection with the accompanying drawings and the letters of reference marked thereon, to be a full, clear, and exact description of the 10 same, and which said drawings constitute part of this specification, and represent, in—

Figure 1, a face view; Fig. 2, a horizontal section.

This invention relates to a design for clock- 15 cases, and the design consists in the configuration and ornamentation as shown in the accompanying illustrations.

The case is substantially elliptical in form, and straight at the back.

20 The base A of the case is rounded, and curves sharply inward, and then outward, forming a narrow rib B, the projecting base and depression above it being ornamented by a series of scroll ornamentations C, in low 25 relief.

The center of the case, which has the usual dial-opening D partially surrounded by a ribbed border E, curves sharply backward, and is surmounted by a plain overhanging canopy F, slightly curved upward at the center, to conform to the curve of the dial opening. 30

At each side of the case projects a series of elaborate shell and scroll ornaments G, springing from the base, and curving upward toward the top, where they are met by a similar canopy H, and curving downward, form a central shell ornament I, forming the apex of the case, all as shown in the accompanying 35 illustrations.

I claim—

40 The design for a clock-case as herein shown and described.

In testimony whereof I have signed this specification in the presence of two subscribing witnesses.

JOHN HOPSON, JR.
